UNITED STATES PATENT OFFICE.

RICHARD W. BURNETT, OF CHICAGO, ILLINOIS.

CAR ROOF.

Application filed December 19, 1921. Serial No. 523,284.

To all whom it may concern:

Be it known that I, RICHARD W. BURNETT, a citizen of the United States of America, residing at Chicago, in the county of Cook and State of Illinois, have invented certain new and useful Improvements in Car Roofs, of which the following is a specification, reference being had therein to the accompanying drawings.

The invention relates to car roofs of the rigid all-metallic type and consists in various features of construction as hereinafter set forth.

In the drawings:

Figure 1 is a sectional perspective view showing a portion of the roof;

Figure 2 is a cross-section;

Figure 3 is a longitudinal section;

Figure 4 is an enlarged view of a portion 20 of Figure 2.

In the construction of car roofs it is usual to connect the side plates of the car by car-lines and to attach the roofing sheets either rigidly or flexibly to said carlines. With 25 my present construction the carlines, as a separate unit, are dispensed with, but the roof is thoroughly reinforced to take care of both compression and tension stresses by the construction of the roofing sheets.

In detail, A are the side plates of a car which, as shown, are in the form of Z-bars. B are the roofing sheets which are curved to 35 arch over the car between the side plates and are provided with down-turned portions secured to the web of the Z-bar. The sheets B at their opposite edges are provided with up-turned flanges C and C', terminating respectively in the laterally-extending flanges D and D', the one overlapping the other.

The upper flange D' is further provided with a downturned end portion E which forms a water shed and protects the joint. The upstanding flanges C and C' are riveted 40 to each other, as indicated at F, and the downturned portions B' are riveted to the web of the plate, as indicated at G. Thus, the flanges C, C', D, D', and E, together with the plates B, form a truss or Z-bar construction which will impart great rigidity, not only to the roof but also the car 45 frame.

In the forming of the sheets the structure is simplified by dispensing with the flange E on the downturned portion of the sheet. 50 Additional reinforcement may, however, be

provided by the use of a reinforcing member H, which is riveted to the flanges C and C' extending around the bend and adjacent to the side plate.

What I claim as my invention is:

1. In a car roof, the combination with side plates, of metallic load sustaining roofing sheets arching between said side plates and rigidly secured thereto, upstanding flanges on the opposite edges of said sheets provided with laterally-extending flanges turned in the same direction, the lateral flange on one sheet overlapping the flange on the opposite edge of the adjacent sheet and said upstanding flanges lying adjacent and being rigidly secured to each other.

2. In a car roof, the combination with side plates, of metallic load sustaining roofing sheets arching between said side plates and rigidly secured thereto, upstanding flanges on the opposite edges of said sheets terminating in laterally-extending flanges turned in the same direction, one of said flanges overlapping the flange of the adjacent sheet, corresponding to the opposite flange of the same sheet, and said overlapping flange having a downturned portion for protecting the joint between the same and the lower flange, and rivets securing said upstanding flanges to each other.

3. In a car roof, the combination with side plates, of metallic load sustaining roofing sheets arching between said plates and rigidly secured thereto, upstanding flanges on the sides of said sheets abutting against the corresponding flanges of adjacent sheets and riveted thereto, said upstanding flanges having laterally-extending flanges turned in the same direction, the one overlapping the other and having a downturned portion for protecting the joint therebetween, said laterally-extending flanges forming compression members for reinforcing said sheets.

4. A single-course car roof comprising a plurality of self-sustaining roof sheets whose adjacent marginal portions are formed into stiffening ribs of substantially L-shaped section that are disposed web to web and are positively secured together to form rigid weather-proofing seams.

5. A single-course car roof comprising a plurality of self-sustaining roof sheets extending from eaves to eaves and having their adjacent marginal portions formed into ribs of substantially L-shaped section that are dis-

posed web to web and are rigidly secured together to form rigid weather-proofing seams that function as carlines.

6. A single-course car roof comprising a plurality of self-sustaining roof sheets extending from eaves to eaves and having their adjacent side marginal portions formed into upstanding seam flanges, each of said seam flanges comprising a substantially vertical

web portion at the top of which is a laterally projecting flat flange portion, the seam flanges of adjacent sheets being rigidly secured together web to web with their lateral flat flange portions lapped to form weather-proofing seams that constitute rigid trans- 15
verse stiffening members for the car.

In testimony whereof I affix my signature.

RICHARD W. BURNETT.
